UNITED STATES PATENT OFFICE.

GEORGE M. LITTLE, OF PITTSBURGH, PENNSYLVANIA, ASSIGNOR TO WESTINGHOUSE ELECTRIC & MANUFACTURING COMPANY, A CORPORATION OF PENNSYLVANIA.

MEANS FOR PRODUCING A SOOTY VAPOUR IN ELECTRIC FURNACES.

Application filed March 23, 1922. Serial No. 546,014.

To all whom it may concern:

Be it known that I, GEORGE M. LITTLE, a citizen of the United States, and a resident of Pittsburgh, in the county of Allegheny and State of Pennsylvania, have invented a new and useful Improvement in Means for Producing a Sooty Vapor in Electric Furnaces, of which the following is a specification.

- 10 My invention relates to electric furnaces and particularly to electric resistance furnaces employing carbonaceous resistors and it has for its object to provide a relatively simple device for producing a sooty vapor 15 in the furnace chamber, which device shall be of relatively high efficiency and embody means for burning out any soot deposited in the device itself.

My invention embodies a substantially closed furnace chamber, in which is located a carbonaceous resistor, and which is provided with a plurality of pipes entering said chamber through one of the walls thereof. A two-position four-way valve is interposed 25 between suitable supply pipes and the pipes entering the furnace chamber and is so arranged that it permits gas to enter the chamber through one of said pipes and permits air to enter through the second of said 30 pipes when the valve is in one of its positions, and permits gas to enter through the second pipe and air through the first pipe when in the other of its positions. Means are provided to vary the relative and actual 35 amounts of air and of gas permitted to enter the respective pipes.

In the single sheet of drawings,

Figure 1 is a view, in vertical lateral cross-section, of an electric furnace comprising the device embodying my invention and

Fig. 2 is a partial vertical, longitudinal section of a furnace of the above indicated character, taken on the line II-II of Fig. 1.

An electric furnace, designated by the numeral 11, comprises a metallic casing or framework 12 which is provided with a plurality of supporting members 13. An outer lining 14 is located within the metallic casing 12 and comprises a plurality of bricks or blocks of a suitable refractory heat-insulating material. An inner lining 15 comprises a plurality of bricks or blocks of a suitable refractory high-temperature resisting material, the bricks or blocks constituting two linings being so shaped and dis-

posed as to provide a furnace chamber 16 of any suitable or desired contour and dimensions. As the furnace is intended to heat treat metallic articles placed in the chamber 16, an opening 17 is provided at substantially the bottom of the furnace chamber and within the front wall thereof.

A heating element 18 is located within the upper part of the furnace chamber 16 and comprises a plurality of relatively thin carbonaceous plates 19 having their flat faces located in abutting relation. A relatively heavy graphite or carbon block 21 is located at each end of the built-up group or flat plates 19 and each block is provided with a depression 22 to operatively engage the inner end of an elongated carbonaceous electrode 23 which extends through an opening 24 in the furnace wall.

As illustrated in Fig. 1, I may employ two electrodes 23 located in opposed axial alignment although I may employ two heating elements and electrodes located in side-by-side spaced-apart relation.

In order to conduct the current to and from the two electrodes 23, metallic terminal members 25 are provided, each having a centrally disposed opening, substantially of conical form, located therein to operatively engage and closely fit upon the outer tapering end of the electrode 23. Provision may be made for permitting a cooling fluid to traverse the members 25 as by core openings or a cast-in pipe 26. In order to effectively insulate the members 25 from the framework of the furnace, annular members 27 of asbestos or other suitable material may be located in the outer surface of the furnace structure surrounding the terminal member 25. The herein disclosed terminal member is more particularly described and claimed in my copending application, Serial No. 463,221, filed on April 21, 1921, and assigned to the Westinghouse Electric & Manufacturing Company.

In order to provide a resilient compression means to maintain the plates 19 and the plates 21 in their proper operative position relatively to each other I provide a helical spring 28 at each end of the furnace with the inner end of the spring presser against a metal plate 29 which is insulated from the metallic terminal member 25 by a plate 31 of a suitable insulating material. An adjusting screw 32 operatively engages the

outer end of the spring 28 and traverses a fixed member 33 to permit of adjusting the amount of compression applied to the electrodes 23, the plates 19 and the blocks 21. 5 While I have illustrated a specific embodiment of a resilient compression means, any device suitable for the purpose may be employed.

A furnace of the above indicated character is more specifically described and claimed in my copending application, Serial No. 454,776, filed on March 23, 1921, and assigned to the Westinghouse Electric & Manufacturing Company, to which application reference 10 may be had for further details. I have found it highly desirable in furnaces of the above indicated type to provide means for producing either a reducing atmosphere or, more preferably, to provide a sooty vapor 15 in the furnace chamber to protect the carbonaceous heating element 18 against the oxidizing effect of air entering through the opening 17 or along the terminal members 25 and the carbonaceous electrodes 23, or 20 even through minute openings between the bricks or blocks of the two linings.

A means for producing a sooty vapor in the furnace chamber comprises two pipes 34 and 35, suitably secured against the bottom of the metallic casing 12 and registering with openings 36 and 37, not only in the casing itself but also through the bottom wall of the two linings. A plug 38 may be located in the lower end of each of the 30 pipes 34 to normally close the same but to permit of ready and quick removal therefrom in case of necessity. Two supply pipes 39 and 40 are provided, one of which, as, for instance, the pipe 39, may be connected to 35 a suitable source of supply of a hydro-carbonaceous gas. The pipe 40 is open at its outer end to the atmosphere. Valves 41 are provided in each of the pipes 39 and 40 to 40 suitably control the amount and ratio of gas and of air permitted to enter the two pipes.

A four-way valve 42 is connected between the inner end of the pipes 39 and 40 and the pipes 34 and 35, respectively, by short lengths of pipe 43 and 44. An operating 45 handle 45 permits of so adjusting the valve that gas is permitted to flow from pipe 39 through pipe 44 into pipe 35 and from thence through the opening 37 into the furnace chamber 16, while, at the same time, air is permitted to enter through the pipe 40 and pipe 43 into the pipe 34 and from thence into the chamber 16 through the opening 36. When the operating handle 45 is moved to the other of its operating positions, 50 the gas from the pipe 39 is permitted to enter the furnace chamber through the pipes 43 and 34 and the opening 36, while air flows through pipes 44 and 35 and into the opening 37.

55 As the heating element 16 is operated at

a relatively high temperature, the inner lining 15 of the furnace chamber also operates at a relatively high temperature and the gas permitted to enter the furnace chamber through either the opening 36 or 70 37 readily ignites and burns to produce a sooty vapor which is carried upward by such slight draft as may be caused by air entering the opening 17 and is deposited not only upon the outside surface of the 75 entire heating element but also upon the exposed inner ends of the electrodes 23 and upon the walls of the furnace chamber. As there is only a slight draft as the amount of gas permitted to flow into the 80 furnace chamber is relatively small, a portion of the soot produced by the burning gas is deposited in that opening through which gas flows into the furnace chamber and, of course, tends to choke or close up 85 that opening. After gas has been permitted to flow through, say opening 37, for a certain length of time and it is noted that there appears to be a deposit of carbon on the floor of the furnace chamber immediately adjacent to or in the opening 37, the operating handle 45 may be so moved as to cause the gas to flow into the furnace chamber through the opening 36 and this action permits air to enter the opening 37. 90 The oxygen of the air combines with the soot deposit and oxidizes the same, thereby removing the soot originally deposited by the action of the burning gas and cleaning out the opening 37. If, after a certain 100 length of time it is noted that a deposit of soot is again visible, this time adjacent to or covering the opening 36, the four-way valve may be again moved to its other position, whereby the gas will be permitted to 105 enter through the opening 37, which has been cleaned out by the action of the air and the air is permitted to flow through the opening 36 to remove the deposit therefrom. By adjustment of the valves 41 in the 110 pipes 39 and 40, the amount of gas and air may be suitably adjusted to meet the operating requirements of the furnace.

The device embodying my invention thus provides a relatively simple means for producing a sooty vapor in a furnace chamber and also provides relatively simple manually controlled means for alternating the flow of gas and of air through any one of the plurality of openings whereby the device is operative to produce a sooty vapor substantially continuously, while, at the same time, providing means for quickly and easily burning out any soot deposited upon or in the opening through which the gas 120 has been flowing.

Various modifications may be made in the device embodying my invention without departing from the spirit and scope thereof and I desire that only such limitations shall 130

be placed thereon as are imposed by the prior art or are specifically set forth in the appended claims.

I claim as my invention:

1. An electric furnace comprising a plurality of walls enclosing a furnace chamber, a carbonaceous resistor located in said chamber, a plurality of feed-pipes entering said chamber and a single means for permitting a fluid sooty-vapor-producing agent to enter said chamber through one pipe and a fluid oxidizing agent through the other pipe.
2. An electric furnace comprising a plurality of walls enclosing a furnace chamber, a carbonaceous resistor located in said chamber, a plurality of feed-pipes entering said chamber, and a single means for alternately permitting a fluid sooty-vapor-producing agent to enter said chamber through one of said pipes and a fluid oxidizing agent through the other of said pipes for removing any soot deposited therein.
3. An electric furnace comprising a plurality of walls enclosing a furnace chamber, a carbonaceous resistor located in said chamber, a plurality of feed-pipes entering said chamber, a single means for alternately permitting a fluid sooty-vapor-producing agent to enter said chamber through one of said pipes and a fluid oxi-

dizing agent through the other of said pipes for removing any soot deposited therein, and means for regulating the respective amounts of oxidizing and sooty-vapor-producing agents admitted to said chamber.

4. In an electric resistance furnace comprising a carbonaceous resistor located in a furnace chamber, in combination, means for reducing the oxidation of said carbonaceous resistor comprising a pair of pipes, a single means for alternately permitting a hydro-carbonaceous gas to enter through one of said pipes to be burned in said chamber to produce a sooty-vapor therein, and for permitting air to enter through the other of said pipes to burn away any soot deposited therein by said burning gas.

5. An electric furnace comprising a plurality of walls enclosing a furnace chamber, a carbonaceous resistor located in said chamber, a plurality of feed-pipes entering said chamber and a single means for selectively and alternately permitting a fluid sooty-vapor-producing agent and a fluid oxidizing agent to flow through said pipes.

In testimony whereof, I have hereunto subscribed my name this 21st day of March, 1922.

GEORGE M. LITTLER
